UNITED STATES PATENT OFFICE

GEORGE W. NESBITT, OF SYCAMORE, ILLINOIS

NESTING DEVICE

Application filed June 13, 1928. Serial No. 284,903.

My invention relates to nesting devices, and more particularly to a novel basket adapted for cooperation with a fibrous or paper stock nest bowl.

5 The object of my invention is to provide a device of the kind described assuring a more ventilated and sanitary condition of a nest suitable for poultry raising.

Another object of my invention is to provide 10 a combination basket and nest bowl of a type particularly adapted for quantity production.

Other objects and advantages of the construction and combination of elements set 15 forth will appear more fully in the present specification when taken in connection with the accompanying drawings, in which:

Figure 1 is a cross sectional view of my invention.

20 Figure 2 is a plan view of the basket employed in my device.

Figure 3 is a transverse section taken on the line 3—3 of Fig. 2 of the basket employed in my device.

25 Figure 4 is a plan view of the nest bowl.

Figure 5 is a cross section of the nest bowl shown in Fig. 4.

Figure 6 is a fragmentary detail view of the means employed to secure the basket to 30 any convenient object.

In the drawings wherein similar characters of reference indicate corresponding parts in the several views, A designates the basket comprising my invention, the basket being formed of two strap members 11 and 12 which are riveted together at right angles as best shown in Figure 2. The ends of each of the strap members are provided with bent edges 13 which serve to clasp the nest bowl, 35 to be hereinafter described, while lugs 14 are

40 stamped from the straps in a manner to provide a means of engaging and securing a wire loop 15, which, as best shown in Figure 3, is passed around the basket and then secured by the bending in of the lugs 14.

The completed nest comprises a bowl 16 formed of paper or fibrous stock. The bowl 16, as shown in Figures 1 and 3 is adapted to seat within the basket A, and then to be 45 securely retained therein by the bending

down of the edges 13. In actual practice I have found that the edges 13 may be left in bent condition, it merely being necessary to insert the flexible edges of the bowl 16 under the folds of the bent edges. It is to be understood that the baskets A are nailed or otherwise suitably secured to a board, table, or other convenient object by means of nails, two of which passed through the diagonally opposite holes 17 in the straps 11 and 12 will suffice to fasten the basket. After one nesting, or whenever it is deemed advisable for sanitary purposes to renew the nest bowl, the latter may be instantly removed from the basket and a new one inserted under the 65 folded edges 13 referred to above.

In addition to the sanitary features provided by my invention, I have found it highly advantageous for quantity production to 70 make the basket by first die-stamping sheets of metal into the form of straps, and then riveting these straps together at right angles. The same stamping operation also provides the lugs 14. The completed basket is now formed by inverting and then passing the 75 wire loop 15 over the conical shaped sides until the lugs 14 are encountered which are then pressed into the position shown in Figure 3. These operations are preferably accomplished by machine methods, but the 80 bending of the edges 13 and the lugs 14 could be done by hand, if desired. The bowls 16 are made of paper stock or other suitable fibrous material, their cost being nominal. If desired, the strap members 11, 12 could 85 be made of wire, but I prefer the sheet metal straps illustrated, since they provide a light, thoroughly ventilated structure while affording a more substantial support for the flexible bowl.

It is to be understood that I have described and illustrated merely a preferred form of my invention, since the device is susceptible of wide modification and variation. I do not wish, therefore, to be limited to the precise 90 details as set forth, but desire to avail myself of such embodiments and changes as fairly lie within the scope of the appended claims.

What I claim as new and desire to secure 95 by Letters Patent is:

1. A nesting device comprising a plurality of metal straps disposed in crossed relation to each other and secured at the points of contact, the ends of said straps being bent upwardly to form a nest basket, a lug provided adjacent the end of each strap, a metal ring member adapted to be engaged by said lugs, a nest bowl of fibrous material disposed within said basket, and a projection upon the end of each strap adapted to be bent into engagement with the upper periphery of said bowl, substantially as described.

2. A nesting device comprising a plurality of metal straps disposed in crossed relation to each other and secured at the points of contact, the ends of said straps being bent upwardly to form a nest basket, a lug portion provided adjacent the end of each strap, a metal ring member adapted to be engaged by said lug portions, and a nest bowl of fibrous material disposed within said basket.

In testimony whereof I have signed my name to this specification.

GEORGE W. NESBITT.
